DESIGN FOR A SIGNAL LAMP UNIT

Harold B. Donley, Columbus, Ohio, assignor to
Columbus Metal Products Inc., Columbus,
Ohio, a corporation of Ohio

Application April 17, 1936, Serial No. 62,179

Term of patent 7 years

To all whom it may concern:

Be it known that I, Harold B. Donley, a citizen
of the United States, residing at Columbus, in
the county of Franklin and State of Ohio, have
invented a new, original, and ornamental Design
for a Signal Lamp Unit, of which the following
is a specification, reference being had to the accompanying
drawing, forming a part thereof.

Fig. 1 is a perspective view of the signal lamp
unit showing my new design;

Fig. 2 is a side view thereof;
Fig. 3 is a rear elevation;
Fig. 4 is a plan view.

The essential feature of my design resides in
the bracket and lens holding portion.

I claim:

The ornamental design for a signal lamp unit,
as shown and described.

HAROLD B. DONLEY.
